DESIGN FOR A CLOTHES HANGER GUARD

George C. Linney, Kansas City, Mo.

Application July 11, 1936, Serial No. 63,798

Term of patent 14 years

To all whom it may concern:

Be it known that I, George C. Linney, a citizen of the United States, residing at Kansas City, in the county of Jackson and State of Missouri, have invented a new, original, and ornamental Design for a Clothes Hanger Guard, of which the following is a specification, reference being had to the accompanying drawing, forming a part thereof.

Fig. 1 is a top perspective view of a clothes hanger guard, showing my new design.

Fig. 2 is a bottom perspective of the same, and, Fig. 3 is a top plan view of the clothes hanger guard.

I claim:

The ornamental design for a clothes hanger guard, as shown.

GEORGE C. LINNEY.
